RECORDING APPARATUS FOR BLOOD
SEDIMENTATION TESTS

Avenir P. Proskouriakoff, Lansdowne, Pa.

Application April 3, 1937, Serial No. 134,893

4 Claims. (Cl. 234—1.5)

My invention relates to recording apparatus for blood sedimentation test and has particular reference to apparatus for determining and recording the rate, index and time of blood sedimentation.

Blood, as is known, consists of cells and a transparent liquid or plasma. The cells are in a state of suspension and they render the blood opaque, having higher refractive index than plasma. The 10 cells, however, do not remain long in suspension if blood, when rendered non-coagulable, is left standing in a container but slowly precipitate, forming an opaque sediment and leaving a clear demarkation line between plasma and cells. 15 This line gradually moves down as the cells become packed more closely in the lower portion of the container. By observing the movement of the demarkation line it is possible to determine the rate of sedimentation.

It has been found that this rate of sedimentation has very different characteristics, depending on the state of health of an individual whose blood is being tested. The rate is very slow for the blood of a healthy individual but becomes 25 relatively rapid in certain pathological cases. By measuring the relative rate of sedimentation it is possible to determine whether a certain suspected illness is present in a patient. This test is especially valuable for determining the degree of 30 activity of various inflammatory processes, and particularly in cases of active tuberculosis.

The value of such tests for diagnosis of certain diseases has been recognized by the medical profession, so that the blood sedimentation test represents now a regular routine practice in hospitals and sanatoriums, and charts are drawn by taking observations at more or less frequent intervals of time of blood in a test tube. Such a 35 method of preparing charts is not very reliable, however, as the result depends on the accuracy of observations and regularity of time periods when observations are taken, adding to the burden of work of hospital attendants.

I have found, however, that it is possible to 45 provide a mechanism which can automatically draw a chart of the sedimentation index for a definite period of time, such as one hour. One of the objects of my invention is therefore to 50 provide means to indicate on a sheet of paper positions of the demarkation line between plasma and blood cells. For this purpose I provide a holder for a test tube containing blood being tested, the holder being movably supported so as 55 to be adjustable in the vertical direction and

being provided with an extension arm with a pen or similar writing instrument. The pen is in contact with a sheet of paper removably fastened to the surface of a cylinder which is slowly turned by a clock mechanism. The holder with the test tube is set in a position where the surface of the blood in the tube corresponds to a starting point, when the pen will draw a zero line on the paper. I also provide means to move the holder with the test tube in accordance with the change 10 of position of the demarkation line in the tube. For this purpose I provide a source of a narrow beam of light which remains stationary and is directed on a phototube across the test tube. I enclose the phototube in an opaque casing with 15 a narrow slot for the light, the path of the light beam determining the zero position of the test tube. I further provide a mechanism operated by an electric motor for raising the test tube support so as to maintain the demarkation line in 20 the path of the beam of light. I arrange the electrical connections in such a manner that the motor becomes energized when the phototube is activated by the beam from the source of light, raising the tube until the opaque portion of the 25 liquid shuts off the light, disconnecting the motor circuit and causing it to stop. The result is that the tube supporting mechanism gradually rises so as to maintain the line of demarkation just above the beam of light. 30

Another object of my invention is to provide means to increase the length of travel of the pen in order to obtain the curve on a larger scale. For this purpose I provide a lever one end of 35 which is connected to the test tube casing, the other, through hinged links, is provided with a pen in contact with the paper on the cylinder.

Another object of my invention is to provide means to cause the pen to move in a straight 40 line, preferably vertical. For this purpose I form the lever mechanism of parallel links so connected that both ends move in straight vertical directions.

Still another object of my invention is to provide means to adjust the position of the casing with reference to the driving mechanism so that the demarkation line can be placed exactly in the path of the beam of light before starting the 50 operation of the mechanism. For this purpose I provide a clutch in the drive, made so that it becomes operative when the test tube is inserted in the casing.

My invention is more fully described in the 55

accompanying specification and drawing in which—

Fig. 1 is an elevational view of my apparatus partly in section, with the lamp removed.

5 Fig. 2 is a top plan view of the same partly in section.

Fig. 3 is an end view of the same partly in section.

10 Fig. 4 is a view of a chart with several index curves.

15 My apparatus consists of a hollow base 1 on which a bracket 2 is mounted supporting a top plate 3. The latter has a hole in one end in which slides a tubular casing 4 for a test tube 5. The casing has upper and lower flanges 6 and 7 with holes slidably fitted over posts 8 held between the base and the top plate.

20 The lower flange 7 has an additional hole which slidably fits over a vertical screw 9 extending into the base by its lower end and connected with an electric motor 10. A spring wire 11 is fastened by one end to the lower side of the flange 7 by a screw 12. The other end of the spring is curved to fit between the threads of the screw. The middle

25 portion of the spring passes through a slot 13 in the casing 4. The spring is set so that its resiliency tends to push it away from the screw 9, but the tube 5, when inserted into the casing, pushes the spring outward, pressing its end 30 against the screw. In this operative position the spring acts as a nut so that when the motor is rotating, the screw pushes the flange 7 upward together with the casing and test tube. The spring forms a clutch between the driving screw 35 and the casing so that the casing can be set in any position above the base 1 by holding it in hands and inserting the test tube until the spring 11 engages the screw. The casing has a slot 14 in one side extending between the flanges 6 and 7.

40 The test tube is filled with blood to the level of a mark 15 near the upper end of the slot 14. An electric lamp 16 is supported on the base at one side of the casing 4 and is enclosed by a metal tube 17 with a cap 18 and provided with a narrow 45 slot 18' on the level of the mark 15 when the casing 4 is in its lowest position. A narrow beam of light thereby passes through the test tube at the mark 15. The other side of the casing has a slot 19 permitting the beam of light to pass through 50 the casing 4 and to fall on a phototube 20 supported on the base 1. The phototube is covered by a metal enclosure 21 with a narrow slot 22 for the beam of light. The slot 22 is substantially 55 on the same level as the slot 18.

55 The casing 4 has shield plates 23 extending from the sides of the slot 19 to the enclosure or cover 21 of the phototube in order to prevent any light from reaching the phototube except through the slot 22.

60 The flange 7 has a pivot 24 at one corner for links 25 and 26. The other end of the link 25 is pivotally connected at 27 to one end of a link 28 the other end of which is pivotally connected at 29 to a bar 30. The end of the bar 30 is pivotally 65 connected with the link 26. The links 26 and 28 are double in order to balance the pull on the bar 30. The link 28 is pivotally supported at 31 on the bracket 2, the point 31 being nearer the lower end of the link 28 than to its upper end in order 70 to cause the outer end of the bar 30 to move in a straight line in vertical direction when the flange 7 with the casing 4 is moved. The bar 30 is considerably longer than the links so that its end correspondingly magnifies the movements of the 75 casing 4. The end of the bar 30 has a hole for a

pen 32 which touches a sheet of graph paper 33 on a cylinder 34. The cylinder 34 is mounted on a shaft 35 the upper end of which is journaled in the plate 3, and the lower end is connected with a clock mechanism 36. The latter may be an 5 electric clock or asynchronous motor properly geared so as to cause the cylinder or drum 34 to make one revolution in about one hour.

The apparatus is connected to an outside power circuit through a flexible cord 37 and has a switch 10 38. The lamp 16 is directly connected to the outside circuit while the motor 10 is connected through the phototube, the latter operating through an ordinary amplifier and relay 39.

Phototubes with amplifiers and relays have 15 been standardized and are now commercially available in complete sets for various purposes. For the applicant's purposes a General Electric unit CR505-A5 can be used, consisting of a phototube connected by a flexible cable with a box 20 containing the amplifier and relay. This unit is fully described in the General Electric bulletin GEA-16545. Suitable units are also described in the Westinghouse bulletin TD-76.

25 The operation of my apparatus is as follows.

The tube 5 is filled with blood to be tested up to the mark 15 and is placed in the casing 4, holding the latter in the lowest position or position in which the mark 15 is placed in the path of the beam of light from the lamp 16. The pen 32 is 30 filled with ink and brought in contact with the paper 33. The latter may be any ordinary sectioned paper calibrated in fractions of an hour along the cylinder circumference. The current is then turned on, causing the lamp 16 to throw a 35 beam of light through the slots 18', 14, 19 and 22 on the phototube 20. It should be noted that the latter may be of any ordinary type, gas filled or vacuum, or a photocell may be used instead with selenium or similar photoelectric materials. The 40 motor, however, will not turn if the casing 4 has been placed so that the blood level is higher than the beam of light, shutting it off the photoelectric element. The pen 32 will then draw a horizontal line which will be a zero line. If, however, the 45 blood level in the tube is below the beam of light, then the motor will turn, raising the tube until the light is shut off, so that there will appear a short vertical line on the paper before the zero 50 line commences to be drawn.

55 The red cells in the blood will gradually begin to settle to the bottom of the tube, leaving clear plasma in the upper portion of the tube 5. As soon as the level of the red cells drops below the upper edge of the light beam, the motor 10 will 60 begin to turn, receiving its current through the relay which is now energized by the phototube. The tube will be again raised until the light is shut off from the phototube, when the rotation 65 will stop. It follows that the casing with the tube 5 will adjust itself to a new position by very fine steps as the cells continue to settle down in the tube 5.

70 As a result, the pen 32 will draw a curve on the paper 33. When the blood is taken from a healthy individual, a characteristic curve 39 will be drawn (Fig. 4), going down very slowly, because the blood in this case precipitates its cells at a very slow rate, usually requiring over two hours to reach a stationary state. This is a normal curve or sedimentation index. A more or less serious illness, however, changes considerably 75 properties of the blood in this respect, and curves 40 and 41 represent such sedimentation indices which prove beyond any doubt that the patient

has a sickness which may be only suspected by other symptoms. It has been found that one hour is quite sufficient time for the determination of the character of the sedimentation index. I 5 provide the cylinder 34, therefore, with a lug 43 which opens a switch 42 upon completion of one revolution which takes one hour. For starting the cylinder it is manually returned to the original position after a new graph paper has been 10 fitted.

It is obvious that my apparatus can be also used for the determination of sedimentation time of various other suspensions or liquids containing an opaque matter which settles at a more 15 or less slow rate, or for testing the degree of fineness of solid materials by their rate of precipitation from liquids.

It is understood that my apparatus may be further modified without departing from the 20 spirit of my invention as set forth in the appended claims.

I claim as my invention:

1. A recording apparatus for sedimentation test of liquids containing an opaque matter in 25 suspension, comprising a vessel for the liquid to be tested, means to movably support the vessel, a photoelectric element supported at the side of the vessel, means to produce a narrow beam of light, means to direct the beam of light through 30 the vessel on the photoelectric element, means to move the vessel in a substantially vertical direction, means to control the vessel moving means by the photoelectric element for maintaining the line of separation of the opaque matter 35 from the transparent liquid at a substantially constant height, and means to exhibit the relative movement of the line of separation in the vessel.

2. A recording apparatus for sedimentation 40 test of liquids containing an opaque matter in suspension, comprising a vessel for the liquid to be tested, means to movably support the vessel, a photoelectric element supported at the side of the vessel, means to produce a narrow beam of light, means to direct the beam of light through 45 the vessel on the photoelectric element, means to move the vessel in a substantially vertical

direction, means to control the vessel moving means by the photoelectric element for maintaining the line of separation of the opaque matter 5 from the transparent liquid at a substantially constant height, and means to exhibit the magnitude of movement of the line of separation with reference to definite periods of time.

3. A recording apparatus for sedimentation test of liquids containing a relatively opaque matter in suspension, comprising a vessel for a 10 liquid to be tested, means to movably support the vessel in a vertical direction, a photoelectric element supported at the side of the vessel, means to produce a narrow beam of light, means to direct the beam of light through the vessel 15 against the photoelectric element, means to move the vessel supporting means in a vertical direction, means to control the moving means by the photoelectric element for maintaining the line of separation of the opaque matter from the 20 transparent liquid at a constant height, means to exhibit the magnitude and rate of movements of the vessel supporting means, a detachable connection between the vessel supporting means and the moving means, and means to render the 25 detachable connection operative by the placement of the vessel in the supporting means.

4. A recording apparatus for sedimentation test of liquids containing a relatively opaque matter in suspension, comprising a vessel for a 30 liquid to be tested, means to movably support the vessel, a photoelectric element supported at the side of the vessel, means to produce a narrow beam of light, means to direct the beam of light through the vessel against the photoelectric element, means to move the vessel supporting means in upward direction, means to render the moving means operative by the photoelectric element when the latter receives the beam of light, means to prevent the downward movement 35 of the supporting means when the moving means is rendered inoperative, means to reset the supporting means in the starting position upon completion of the test, and means to exhibit the magnitude and rate of movements of the sup- 40 porting means.

AVENIR P. PROSKOURIAKOFF.
